US00D861788S

(12) **United States Design Patent** (10) Patent No.: **US D861,788 S**
Kihl et al. (45) Date of Patent: ** Oct. 1, 2019

(54) **DIGITAL SIGN**

(71) Applicant: **LG ELECTRONICS INC.**, Seoul (KR)

(72) Inventors: **Hewon Kihl**, Seoul (KR); **Yongho Lee**, Seoul (KR); **Hyeyoung Hong**, Seoul (KR); **Jungyeon Hwang**, Seoul (KR)

(73) Assignee: **LG ELECTRONICS INC.**, Seoul (KR)

(**) Term: **15 Years**

(21) Appl. No.: **35/504,598**

(22) Filed: **Sep. 22, 2017**

(80) **Hague Agreement Data**

Int. Filing Date: **Sep. 22, 2017**

Int. Reg. No.: **DM/100078**

Int. Reg. Date: **Sep. 22, 2017**

Int. Reg. Pub. Date: **Mar. 16, 2018**

(30) **Foreign Application Priority Data**

Mar. 24, 2017 (KR) 30-2017-0013867

(51) LOC (12) Cl. **20-03**

(52) U.S. Cl.

USPC **D20/10; D25/18**

(58) **Field of Classification Search**

USPC **D14/373, 127; D20/10, 17, 19, 21; D25/18**

CPC **G09F 7/00; G09F 13/04; G09F 19/02**
See application file for complete search history.
